L. G. BLACK

AIR BRAKE MECHANISM

Filed March 30, 1921

INVENTOR.

L.G. BLACK

BY Milton S. Brandall
ATTORNEY

UNITED STATES PATENT OFFICE.

LESLIE G. BLACK, OF SIOUX CITY, IOWA.

AIR-BRAKE MECHANISM.

Application filed March 30, 1921. Serial No. 457,022.

To all whom it may concern:

Be it known that I, LESLIE G. BLACK, a citizen of the United States, and a resident of Sioux City, in the county of Woodbury 5 and State of Iowa, have invented certain new and useful Improvements in Air-Brake Mechanism, of which the following is a specification.

The railway airbrake systems in common 10 use employ so-called retaining valves, mounted on every coach and car and so associated with the triple valves as to retain a light breaking pressure, when the retaining valves are closed.

15 This system suffers from the fact that the retaining valves must be individually manually controlled, which necessitates a trainman going over or through the train to "turn them up" or "turn them down," the 20 terms commonly employed by trainmen for accordingly closing and opening the retaining valves.

A further evil of the system resides in the 25 fact that when the valves are closed the brakes are energized until the valves are opened. For example, when the retaining valves have been "turned up" prior to descending a gradient, they are left in this 30 position during the entire descent and the brakes remain energized until trainmen again open the retaining valves, which requires considerable time, if the train is long. At the foot of the gradient the train must 35 be brought to a stop until the valves are again opened, or the brake pressure opposes the power of the locomotive.

40 My invention has, therefore, for its primary object the production in an air-brake system of means which obviate the above-recited evils and objections, and places the retaining valves under the control of the engineman.

A further object of the invention is the 45 production in an air-brake system of improved means whereby the retaining valves are automatically and simultaneously controlled by the train-line pressure.

Still another object of the invention is the 50 production in an air-brake system of improved means for the automatic control of

the retaining valves which is comparatively simple and inexpensive in construction, yet thoroughly dependable and efficient in operation.

These and other objects and advantages 55 are successfully attained in the embodiment hereinafter described, defined in the appended claims and illustrated in the accompanying drawings, which form a part of this application, and in which like characters of reference indicate corresponding parts throughout the several views, of which,—

Fig. 1 is an enlarged vertical section of the device of my invention and the associated triple valve, the parts being shown in 60 normal position and the triple valve being cut away; and

Fig. 2 is a similar view of my device and the triple valve, the parts being shown in 70 operative position.

While I have illustrated and hereinafter described but one embodiment of the invention, I would not be understood as being limited to such specific construction, for 75 various alterations and modifications may be made in the details of construction and arrangement of parts herein disclosed without departing from the spirit and scope of the invention, as defined in the appended 80 claims.

Referring now to the illustrations, I have shown the usual quick-action triple-valve embodying the triple valve body, 4, having the cylindrical chamber, 5, closed by the 85 cylinder cap, 6, and in which reciprocates the triple piston, 7, controlling the slide valve, 8, which normally places the exhaust passage, 9, in communication with the passage, 10, leading to the brake cylinder 90 through the tube 11; and when a reduction is made in the train line, exposes the passage, 10, to pressure from the auxiliary reservoir, 30. 12 is the usual check-valve case, having the induction passage 13, which if 95 will be understood is connected with the train line, 14, whereby pressure from the latter enters the cylinder cap 6, forcing the triple piston 7 inwardly sufficiently to expose the feed-groove 15, whereby pressure 100

enters the auxiliary reservoir through the triple valve-body, 4.

The usual three-way retaining valve is represented by the casing, 16, having a weight-controlled valve, 17, normally closing an exhaust passage 18, registering with a passage 19 in the valve 20, rotated by means of the handle 21 to place the passage 18 in communication with the induction passage 22 of the retaining valve, or, when turned down at right angles, the retaining valve passage 18 is closed, and the valve passages, 19 and 23, register, respectively, with the induction passage 22 and the exhaust passage, 24.

This retaining valve, as now used, communicates with the usual free air exhaust, 9, in the triple valve body.

The structure above described represents no part of my present invention, but serves to illustrate those elements of the air-brake system now in use with which the device of my invention is associated.

Between the triple valve exhaust and the retaining valve is interposed my novel automatic device, which consists, preferably, of two cylinders, 26 and 27, disposed in parallelism, cast en bloc and provided with a hanger, 28, adapted to be secured to the underframe of a car, 29.

Within the cylinder, 26, is a piston, 31, having a stem, 32, carrying a slide valve, 33, within a valve chamber, 34, on the said cylinder. The slide valve, 33, normally closes a port, 35, leading from the chamber, 34, to the opposite end of the cylinder, 27, within which reciprocates a piston, 38, having a stem, 39, carrying a slide valve, 40, positioned in a slide-valve chamber, 41, on the cylinder 27, and provided with a screened exhaust opening, 42, which is normally opened, and when a reduction is made in the train-line pressure the said exhaust opening is closed by the slide valve, 40, as will presently be made more clear.

Between the slide valve, 40, and the head of the valve chamber, 41, is a buffer spring 43, serving to prevent impact of the slide valve with the head of the valve chamber.

The head of the valve chamber is provided with an induction opening, 44, and an education opening, 45, the former being connected by a suitable duct, 46, with the triple exhaust opening, 25; and the latter is connected by a suitable duct, 47, with the induction passage, 22, of the retaining valve.

Between the piston, 31, and the head, 48, of the cylinder, 26, is interposed a compressing spring, 49, the piston, 31, being provided with a second steam, 50, engageable with the stem, 63, of a puppet valve, 52, adapted to co-act with a suitable valve seat, 53, in an opening, 54, in the cylinder head.

The valve, 52, is enclosed in a suitable valve chamber, 54, on the cylinder head, 48,

and closed by a suitable head including a plate, 55, and a central screw plug, 56, therein, between which plug and the valve, 52, is interposed a comparatively light compression-spring, 57, encircling a small stem, 58, on the valve, 52, by virtue of which construction the screw plug may be turned to vary the tension of the spring, 57.

The valve chamber, 54, communicates with the adjacent end of the cylinder, 27, through a suitable port, 59, and between the head, 48, and the piston, 31, the cylinder, 26, is provided with a screened exhaust opening, 60.

The head of the slide valve chamber, 34, is provided with an induction opening, 61, connected by a suitable duct, 62, with the auxiliary reservoir, 30.

The combined tension of the springs, 49, and 57, when compressed, is substantially equal to the normal train line pressure, which, it will be understood, is usually 85 to 95 pounds, and, for example, we will assume that the tension of the spring, 49, under compression is 70 pounds and that of the spring, 57, is 15 pounds. The port, 35, and slide valve, 33, are so related that the normal train line pressure entering the slide valve chamber, 34, from the auxiliary reservoir acts on the piston, 31, to cause the valve, 33, to close the said port and hold the valve, 52, from its seat, permitting pressure within the cylinder, 27, to escape through port 59; the valve chamber 54, the cylinder head opening, 51, and the exhaust opening, 60, all, as clearly illustrated in Fig. 2.

When either a service reduction or an emergency reduction is made in the train line, the pressure within the valve chamber, 34, being thereby reduced, the spring, 49, forces the piston in the direction of the valve chamber, 34, causing the spring, 57, to seat the puppet valve, 52, and the slide valve, 33, to open the port, 35, whereby sufficient pressure within the slide valve chamber, 34, enters the cylinder, 27, through port 35, to force the piston, 38, in the direction of the valve chamber, 41, thereby causing the slide valve, 40, to close the exhaust port, 42, all as presented in Fig. 3, in which view it will be seen that pressure escaping from the triple exhaust into the valve chamber, 41, can escape only through the retaining valve, which, it will be understood, is always closed or "turned up" and in connection with my device functions as usual and retains the pressure for which it is intended, while the slide valve 40, is in the position shown in Fig. 3. Then, when the engineer starts to recharge the train line, the pressure entering the valve chamber, 34, from the auxiliary reservoir acts on the piston, 31, to cause the valve, 33, to blank the port, 35, and as the train line receives its

125
130

final 15 pounds of pressure the puppet valve, 52, is forced from its seat, permitting the pressure entering the valve chamber, 41, to force the piston to the position shown in Fig. 2 to open the exhaust port, 42, through which the braking pressure is then free to exhaust.

By virtue of my construction it will be now clear that the retaining valves are entirely within the control of the enginemen and they offer resistance to the braking pressure only when the train-line pressure is sub-normal.

Having thus described my invention, what I claim as new and desire to secure by Letters Patent of the United States is:—

1. A brake system embodying a source of fluid pressure, brake mechanism including a fluid-pressure passage, an exhaust passage, valve mechanism for placing said passages in and out of intercommunication, a fluid-pressure-retaining valve, a communicating passage between the exhaust passage and the retaining valve, and means for controlling the retaining valve, including a valve chamber communicating with said communicating passage and having an exhaust opening, valve mechanism within said chamber, actuated from said source of pressure to close the exhaust opening when the pressure in said source is subnormal, and actuated by pressure from the communicating passage to open the exhaust opening when the pressure in said source is normal.

2. In a brake system embodying a source of fluid pressure, brake mechanism including a fluid-pressure passage, an exhaust passage, valve mechanism for placing said passages in and out of intercommunication, a fluid-pressure-retaining valve, a communicating passage between the exhaust passage and the retaining valve, and means for controlling the retaining valve, including a valve chamber communicating with said communicating passage, and having an exhaust opening, a second valve chamber communicating with said source of pressure, a port between said chambers a valve in said second chamber governed by normal pressure from said source to close said port, a valve in said first chamber actuated by pressure from the communicating passage to open the exhaust opening when the pressure in said source is normal, and yieldable means for forcing the valve in said second chamber to open said port when pressure in said source is subnormal, whereupon pressure entering said first chamber through said port causes the valve in said first chamber to close the exhaust opening.

3. In a brake system, the combination with a source of fluid pressure, brake mechanism including a fluid-pressure-passage, an exhaust passage, and means for placing said passages in and out of intercommunication,

of a fluid-pressure-retaining valve, a communicating passage between the retaining valve and the exhaust passage and having a normally open exhaust opening, and valve mechanism governed by the source of fluid pressure to close the exhaust opening when the pressure in said source is subnormal, and actuated by pressure from said communicating passage to open the exhaust opening when the pressure in said source is normal.

4. In a brake system, the combination with a source of fluid pressure, brake mechanism including a fluid-pressure-passage, an exhaust passage, and means for placing said passages in and out of intercommunication, of a fluid-pressure-retaining valve, a communicating passage between the retaining valve and the exhaust passage, a valve chamber communicating with the said communicating passage and having a normally open exhaust opening, and slide valve mechanism within the chamber governed by the source of fluid pressure to close the exhaust opening when the pressure in said source is subnormal.

5. In a brake system, the combination with a source of fluid pressure, brake mechanism including a fluid-pressure-passage, an exhaust passage, and means for placing said passages in and out of intercommunication, of a fluid-pressure-retaining valve, a communicating passage between the retaining valve and the exhaust passage, a valve chamber communicating with the said communicating passage and having a normally open exhaust opening, and valve mechanism within the chamber governed by the source of fluid pressure to close the exhaust opening when the pressure in said source is subnormal.

6. In a brake system, the combination with a source of fluid pressure, brake mechanism including a fluid-pressure-passage, an exhaust passage, and means for placing said passages in and out of intercommunication, of a fluid-pressure-retaining valve, a communicating passage between the retaining valve and the exhaust passage, a valve chamber communicating with the said communicating passage and having a normally open exhaust opening, and valve mechanism within the chamber governed by the source of fluid pressure to close the exhaust opening when the pressure in said source is subnormal and governed by pressure from the said communicating passage to close the exhaust opening when pressure in said source is normal.

7. In a brake system, the combination with a source of fluid pressure, brake mechanism including a fluid-pressure-passage, an exhaust passage, and means for placing said passages in and out of intercommunication, of a fluid-pressure-retaining valve, a communicating passage between the retaining valve and the exhaust passage, a valve chamber communicating with the said communicating passage and having an exhaust opening, a second valve chamber communicating with said source of pressure, a port between said chambers, a valve in said second chamber governed by normal pressure from said source to close said port, a valve in said first chamber actuated by pressure from the communicating passage to open the exhaust opening when the pressure in said source is normal, and yieldable means for forcing the valve in the second chamber to open said port when pressure in said source is subnormal; whereupon pressure entering said

first chamber through said port causes the valve in said first chamber to close the exhaust opening.

7. A retaining valve controlling means for a brake system having a source of fluid pressure, a brake-pressure exhaust and a fluid-pressure-retaining valve communicating with the exhaust, comprising a chamber adapted to communicate with the exhaust and having an exhaust passage, and fluid-pressure-actuated valve mechanism adapted to be governed by pressure from the source when said source of pressure is subnormal, to close the exhaust passage, and by pressure from the brake-pressure exhaust to open the exhaust passage when the said source of pressure is normal.

8. A retaining valve controlling means for a brake system having a source of fluid pressure, a brake pressure exhaust and a fluid-pressure-retaining valve communicating with the exhaust, comprising a chamber adapted to communicate with the exhaust and having an exhaust passage, a valve within said chamber actuated by pressure from the brake-pressure exhaust to open the exhaust passage, a second chamber adapted to receive pressure from said source, a passage between said chambers, a valve within the second chamber actuated by normal pressure from the source to hold the latter passage closed, and means for opening the latter passage when the source of pressure is subnormal, whereby pressure enters said first chamber through the latter passage, said first chamber valve being adapted to be forced to close the exhaust passage by pressure entering said first chamber from said second chamber.

9. A retaining valve controlling means for a brake system having a source of fluid pressure, a brake pressure exhaust and a fluid-pressure-retaining valve communicating with the exhaust, comprising a cylinder, having a valve chamber adapted to communicate with the brake pressure exhaust and having an exhaust passage, a piston within the cylinder, a valve within the chamber for the control of the exhaust passage governed by the piston, whereby pressure from the exhaust passage acts on the piston to force the valve open, a chamber adapted to communicate with said source of pressure, a passage between said latter chamber and said first cylinder, whereby pressure enters therein to act on the piston to force said first chamber valve closed, and means controlled by the source of pressure for normally closing the latter passage, and causing it to open when pressure at the source is subnormal.

10. A retaining valve controlling means for a brake system having a source of fluid pressure, a brake pressure exhaust and a fluid-pressure-retaining valve communicat-

ing with the exhaust, comprising a cylinder, having a valve chamber adapted to communicate with the brake-pressure-exhaust and having an exhaust passage, a piston within the cylinder, a valve within the chamber for the control of the exhaust passage governed by the piston, whereby pressure from the exhaust passage acts on the piston to force the valve open, a chamber adapted to communicate with said source of pressure, a passage between said latter chamber and said first cylinder, whereby pressure enters therein to act on the piston to force said first chamber valve closed, means controlled by the source of pressure for normally closing the latter passage and causing it to open when pressure at the source is subnormal, and a normally-open valved exhaust passage from said cylinder controlled by said means.

11. A retaining valve controlling means for a brake system having a source of fluid pressure, a brake pressure exhaust and a fluid-pressure-retaining valve communicating with the exhaust, comprising a cylinder, having a valve chamber adapted to communicate with the brake-pressure-exhaust and having an exhaust passage, a piston within the cylinder, a valve within the chamber for the control of the exhaust passage governed by the piston, whereby pressure from the exhaust passage acts on the piston to force the valve open, a second cylinder having a valve chamber adapted to receive pressure from said source, a passage between the latter chamber and the first cylinder, through which pressure acts on the piston to close said first chamber valve, a piston within the second cylinder, a valve in the second chamber controlled by the second piston to govern the latter passage, said second piston and valve being so constructed and mounted that normal pressure acts on the latter piston to close the latter passage, and yieldable means causing the latter valve to open said latter passage when pressure entering the second chamber is subnormal.

12. A retaining valve controlling means for a brake system having a source of fluid pressure, a brake pressure exhaust and a fluid-pressure-retaining valve communicating with the exhaust, comprising a cylinder, having a valve chamber adapted to communicate with the brake-pressure-exhaust and having an exhaust passage, a piston within the cylinder, a valve within the chamber for the control of the exhaust passage governed by the piston, whereby pressure from the exhaust passage acts on the piston to force the valve open, a second cylinder having a valve chamber adapted to receive pressure from said source, a passage between the latter chamber and the first cylinder, through which pressure acts on the piston to close said first chamber valve, a piston within the second cylinder, a valve in the second chamber controlled by the second piston to govern the latter passage, said second piston and valve being so constructed and mounted that normal pressure acts on the latter piston to close the latter passage, and yieldable means causing the latter valve to open said latter passage when pressure entering the second chamber is subnormal.

ber controlled by the second piston to govern the latter passage, said second piston and valve being so constructed and mounted that normal pressure acts on the latter piston to close the latter passage, yieldable means causing the latter valve to open said latter passage when pressure entering the second

chamber is subnormal, and a normally-open valved exhaust passage from the first cylinder controlled by said second piston.

In testimony whereof, I have hereunto set my hand this 25th day of March, 1921.

LESLIE G. BLACK.
